UNITED STATES PATENT OFFICE.

FRANK H. DURELL, OF BAY CITY, MICHIGAN.

DESIGN FOR AN ADVERTISING-PICTURE FRAME.

SPECIFICATION forming part of Design No. 18,265, dated April 24, 1888.

Application filed August 22, 1887. Serial No. 247,619. Term of patent 14 years.

To all whom it may concern:

Be it known that I, FRANK H. DURELL, a citizen of the United States, residing at Bay City, in the county of Bay and State of Michigan, have invented and produced a certain new, useful, and original Design for Advertising Devices; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 Figure 1 is a front view of my design for advertising-picture frame. Fig. 2 is a section of the same at $x x'$.

The design consists in a large painting or picture provided with a frame, the front surface of which is provided on its outer and inner edges with marginal strips slightly raised above the surface of the front or face of the frame, and with the space between the marginal strips arranged into smaller divisions of a suitable size by raised dividing-strips crossing the space between the marginal strips, and within the said smaller divisions are placed advertising-matter, such as pictures or printing, &c. The painting is of a large size—say 25 about seven by nine feet—and the frame should have a front face of about eight or ten inches in width surrounding the picture.

In the drawings, a represents the picture, and b is the frame.

30 c is a marginal strip slightly raised above the front surface of the frame or the outer edge thereof, and d is a similar marginal strip upon the inner edge of the front surface of the frame.

e are dividing-strips which are placed across the space between the strips c and d , and arrange the surface of the frame into smaller divisions or spaces, f .

The divisions g at the corner of the frame and the divisions h in the central portions of the top, bottom, and side portions of the frame 45 are extended outward and form spaces of somewhat greater area than that of the spaces f , which greatly adds to the symmetrical proportion and general appearance of the frame.

The ground within the several spaces f , g , 50 and h is ornamented with printing or pictures, as desired, the whole forming an advertising device of a neat and attractive appearance.

What I claim, and desire to secure by Letters Patent, is—

55 The design for an advertising-picture frame herein shown and described, consisting substantially of the frame b , surrounding the picture, and provided on the exterior edges of its front surface with the raised marginal strips c and on the inner edge thereof with the raised marginal strip d , and having at intervals across the said surface between the strips c and d the raised strips e and the rectangular spaces f , and having the outwardly 60 projecting and enlarged central spaces, h , 65 substantially as described and shown.

In testimony whereof I affix my signature in presence of two witnesses.

FRANK H. DURELL.

Witnesses:

WILLIAM GOLDIE,
JAS. E. THOMAS.
